UNITED STATES PATENT OFFICE.

THOMAS E. MAJOR, OF MALDEN, MASSACHUSETTS, ASSIGNOR TO THE BOSTON FOOTWEAR MACHINE COMPANY, OF MAINE.

MACHINE FOR TRIMMING EDGES OF UPPERS WITHIN SHOES OR BOOTS.

SPECIFICATION forming part of Letters Patent No. 665,245, dated January 1, 1901.

Application filed January 11, 1896, Serial No. 575,086. (No model.)

To all whom it may concern:

Be it known that I, THOMAS E. MAJOR, a citizen of the United States, residing at Malden, in the county of Middlesex and State of Massachusetts, have invented certain new and useful Improvements in Machines for Trimming the Edges of Uppers within Shoes or Boots, of which the following is a specification.

It is desirable in the manufacture of certain kinds of shoes to remove therefrom a portion of the edge of the lasted upper, or of the upper and lining, after it has been attached to the outsole. In the manufacture of such a shoe a section of an insole—namely, the shank and heel end thereof—is mounted upon the bottom of a last, and there is also attached to the bottom of the last a dummy half-sole section narrower than the bottom of the last, which extends from the shank end 20 of the insole forward and includes the ball and toe. Upon these two sections, the first of which forms a permanent part of the shoe and the second of which is used only for the purposes of lasting, the edges of the upper and the 25 lining are attached in lasting and as though the two sections constituted an ordinary insole. The lasted upper and the two attached sole-sections are then removed from the last, and the upper is permanently united to an out- 30 sole by a seam sewed by the McKay sole-sewing machine or a similar machine or by any other fastening means which pass through the edge of the upper within the shoe, close to the side thereof, and through the outsole, prefer- 35 ably into a channel in its under surface. This uniting-seam extends through the rear part of the sole-section already referred to as forming a permanent part of the shoe; but it preferably passes beyond the outer edge of the 40 dummy-section. The shoe thus made is then subjected to a further process by which the dummy-section and the overlapping edges of the upper and the lining, which were lasted upon it, are removed, the edge or surplus part 45 of the upper and lining being severed from the main part of the upper and lining by means of a mechanism employing a rapidly-reciprocating knife adapted to be introduced within the fore part of the shoe and to cut the 50 edge of the upper and lining close to and within the line of the uniting-seam, but out-

side of the edge of the dummy-piece, from one end thereof, about the toe, to the other end, or completely around it. The dummy-section and edges of the upper and lining may 55 then be readily removed. My invention relates to machines adapted to thus cut within the shoe or other inclosed or partially-inclosed space. Machines for doing this were patented by G. W. Day November 24, 1891, which patents are numbered, respectively, 463,947 and 463,948, and my invention is an improvement in the class to which they belong.

My invention comprises an organization having, among other devices, first, a support 60 or rest upon which the outsole of the shoe bears during the operation of a trimming-knife; second, a reciprocative cutter or knife above the said sole support or rest and a bar-case and guide for the same, which bar-case 65 and guide are adapted to be moved laterally from above the sole support or rest to a position at one side of the same to permit the placing of the shoe over the lower part thereof and its removal therefrom, the cutter, casting, guide, and shoe being movable together 70 to and from the operative position of the cutter over the sole support or rest; third, a gage 75 against which the edge of the sole of the shoe is adapted to be held and guided by the operator while the shoe-sole is upon the sole rest or support and during the operation of the trimming-cutter, which gage determines the line of the cutting action of the reciprocating cutter or knife in respect to the seam 80 that unites the outsole to the upper or other predetermined line, and this gage when positively rotated may also act to assist the operator in the feeding or presentation of the shoe to the cutting instrument; fourth, means 85 for actuating the cutter and for latching the knife-case and guide in operative position and for unlatching them to permit them and the knife to be moved laterally; fifth, means 90 whereby the unlatching of said knife-bar 95 case and guide also serves to automatically lift the knife or cutter in the case to its highest position or within it, if the machine in coming to rest has not so lifted it, and for the purpose of preventing injury to the work or 100 the operator when moved laterally to its inoperative position or while it is being moved

to and from such position; sixth, means for adjusting the sole support or rest vertically and horizontally and the sole-edge gage vertically and horizontally, whereby the relation of these parts to each other and the line of reciprocation of the knife or cutter may be varied at the will of the operator.

It will be understood that the shoe is presented to the machine and fed right side up, 10 that the bottom or under surface of the out-sole rests upon the sole-support with its edge bearing against the gage, that the knife or cutter is held within the shoe by its bar casing or guide, which is shaped at the lower 15 end to so locate it, and that the under surface of the knife-bar case is not brought into contact with the upper surface of the lining or bottom of the shoe, but that there is a clear space generally between the under 20 surface of the knife-bar case and the upper surface of the lining or bottom of the shoe. It will also be understood that the operator guides the shoe during the entire operation of the machine, whereby the above relation 25 of the parts to each other during the entire cutting operation is maintained, and that where the gage is rotated it assists in that it helps to move the shoe.

Reference is to be had to the accompanying drawings forming part hereof, wherein—

Fig. 1 is a view in side elevation of a machine embodying my invention. Fig. 2 is a view in plan thereof. Fig. 3 is a view in vertical section, on the line $x-x$ in Fig. 2, of the upper part of the machine. Fig. 4 is a view in horizontal section upon the dotted line $y-y$ in Fig. 3 and in plan of parts below said line. Fig. 5 is a view in front elevation, enlarged, representing the knife-case and devices for suspending it, locking it in operative position, and for operating the knife. Fig. 6 is a view in elevation, enlarged, of the parts represented in Fig. 5, showing them in full lines in different operative positions 45 from those represented in Fig. 5 and in dotted lines removed laterally from said position and also representing, in connection with Fig. 5, the means for moving the knife to its highest position upon the unlatching of the 50 knife case and guide. Fig. 7 is a detail view, in vertical section enlarged, representing the relation of the boot or shoe to the sole-support, the sole-edge gage, or the knife or cutter when the work is in operative relation to the 55 parts and the parts in operative relation to each other. Fig. 8 is a detail view, in horizontal section, upon the dotted line $z-z$ of Fig. 3.

A indicates the stand or frame of the machine. It is generally made in two parts—60 namely, the base a and the upper section a' —having at its top the forward extension a^2 and at its back the bracket a^3 , shown as integral with section a' . The extension a^2 is hollow, and through it extends the main shaft 65 B of the machine, which has suitable bearings therein and thereon. Means are provided for rotating shaft B and for quickly

stopping its rotation. For this purpose the shaft B carries clutch members b and b' , the driving member b of which clutch is also shown 70 as a belt-wheel and which when disengaged from the driven member b' of the clutch revolves freely upon said shaft. The driving member b also has limited endwise movement upon shaft B . The driven member b' 75 of the clutch is rigidly attached to the shaft and is engaged by the driving member b when it is desired to operate the machine. The means I have shown for this purpose comprise rock-lever b^3 , pivoted at b^4 to the 80 bracket a^3 and connected with a foot-treadle B' by a link or rod b^5 the arm b^2 of lever b^3 being adapted to engage the driving member b . The depression of the treadle causes the driving member of the clutch to be moved 85 into engagement with the driven member and to be held in such engagement by means of arm b^2 , and upon the release of the treadle a spring b^6 , connected therewith, draws the treadle up to remove the pressure of the rock-lever b^3 from the driving member. The rock-lever b^3 also has an arm b^8 , carrying a brake or block b^7 , which acts against the driven member b' of the clutch when the treadle is used to check the rotation of the shaft B after the clutch members b and b' are disengaged. 95

The shaft B is used to actuate a cutter or knife, and for this purpose at the front end carries a crank-pin c , which is connected by 100 a pitman or link c^2 with a knife-bar c' , located in a knife-case C , the knife-bar carrying a knife or cutter C' . As shaft B is rotated rapidly and rapidly reciprocates the knife-bar and knife, I have represented said shaft 105 as provided with a counterbalance c^3 in opposed relation to the crank and knife-bar. The knife or cutter C' is suitably secured to the bar c' . The knife-bar case C may be said to have, for convenience, a general shape, on a 110 diminutive scale, like the lower half of a case made to fit a banjo, with a head c^4 , sharply bent back, held upright end for end, face out, with a cap and plate c^9 covering the circular part and the upper half of the straight 115 part and a plate c^{10} covering the lower half of the straight part, the part c^4 being uncovered on the lower side. The knife-bar case is movably supported, and for this purpose from the center of the circular part a sleeve 120 c^5 extends over the main shaft on which it is journaled, the axis of the shaft B and the case C being concentric. c^6 is a lug or ear carried by the case C , shown on top thereof, the lug or ear c^6 having a latching-recess c^7 , which is 125 adapted to receive a locking-pin d , shown carried by a rocker-arm d^3 . The pin d and lug or ear c^6 serve to hold the case C either vertically or slightly inclined from the vertical, as will hereinafter appear, and thus 130 serve as a lock for the case C .

The circular and the straight part of case C , as illustrated, form three recesses of different depths. The first incloses the coun-

terbalance c^3 , carried by the main shaft, as well as the crank-pin c , and the sleeve or bearing of the pitman c^2 , journaled on it. The second recess is for the play of the pitman, and the third and shallowest recess is for the upper and longer portions of the knife-bearing bar c' . The part c^4 forms a cover for the top and sides of the backwardly-projecting portion of the knife-bar c' , out from under which the bar reciprocates with the knife at its extremity and up and into which both are drawn when the device that raises the locking-pin from its recess rotates the main shaft, as hereinafter shown.

15 It will be seen that the knife-bar is bent at its lower end inwardly and downwardly, and thus carries the knife inside the shoe and there operates it. The bar may be reciprocated in any desired way. The knife-case 20 acts when rigidly locked in a fixed position as a guide to maintain the knife bar or arm in its operative position of rapid reciprocating motion, and it also acts as a cover for said bar and as a means for moving said bar laterally, the bar c' being pivotally supported by the crank-pin c .

The knife-bar case is represented in full lines in Figs. 5 and 6 in its latched position and in Fig. 6 in dotted lines in its unlatched 25 position. In Fig. 5 the locking-pin d is shown in engagement with the latching-recess c^7 of the case, and in Fig. 6 it is represented as disengaged from the latching-recess to allow the case to be moved from the position shown 30 by full lines to the position shown by dotted lines. The locking-pin d projects horizontally from the arm d^3 , and the latter is carried by a rock-shaft d' . The rock-shaft d' is supported by brackets d^4 , which project from 35 the extension a^2 . (See Figs. 1, 2, and 5.) Rock-shaft d' also carries an arm d^2 , that is connected with a treadle D by an arm D' . The treadle D is held in its highest position 40 by a spring d^5 , and this serves to hold the locking-pin d in its lowest position or in a position to automatically engage the latching-recess c^7 when the case C is moved from the 45 position shown by dotted lines in Fig. 6 to the position shown by full lines in Fig. 5. The lug c^6 is extended upward upon one side of the latching-recess to provide a stop beyond which the pin may not pass, and upon the opposite side of the latching-recess it has the inclined surface c^8 , which serves to lift 50 the locking-pin to allow it to pass into recess c^7 of lug c^6 when the latter is moved from its lowest position to its normal operative position.

It is desirable to stop the rotation of shaft 55 B as soon as it is disconnected from its driving devices, and for this purpose the shaft d' also has an arm e' , that carries a roll or pin E , which roll or pin is adapted to engage the edge e^2 of a heart-shaped cam E' , supported by shaft B and shown carried upon the front face of the driven clutch member b' . When the treadle D is moved downwardly, it lifts

locking-pin d from the recess c^7 of lug c^6 and simultaneously brings roll E into engagement with cam E' , thereby turning the shaft B sufficiently to operate the crank-pin and cause it to lift the knife-bar and the knife C' to their highest position, unless, of course, the machine shall have stopped when the crank is in such position. The edge of the heart-cam has a return-curve, forming a recess e^3 , which permits the said roll or pin E to make its full stroke either when the roll or pin acts to move the cam or when the cam has stopped with the said recess in line with the said roll or pin. It will thus be seen that the operation of unlatching the knife-bar case preparatory to the removal of the shoe therefrom automatically causes the shaft and crank-pin to be turned, if the crank-pin is not already 75 in its highest position, to lift the knife from the shoe into the lower end of the knife-bar case, thereby permitting the shoe to be removed without injury to itself or to the knife and permitting the placing of a new shoe upon 80 the lower end of the knife-bar case without injuring the knife or shoe.

It will be understood that the shaft may be turned by the cam and its actuating-pin, because at that time the shaft is at rest, the 95 driving member of the clutch having been disengaged from the driven member. The heart-cam E' may be attached directly to the shaft B instead of to the driven member of the clutch.

Beneath the knife or cutter C' is a support or rest for the outsole. Such a support is shown at F and which is indicated as inclined from its upper end f downwardly and outwardly, and it also preferably broadens 105 from its upper end. The support or rest F is adjustable vertically, and for this purpose it is shown extending to the upper end of a slide f' , which is movable for the purposes of adjustment in a vertical slideway f^2 at the 110 front end of a horizontal bracket F' , which slideway is preferably formed in the end of the bracket. The slide is so represented, and it is covered by a cap-plate f^3 . The means I have shown for allowing vertical adjustment 115 of the slide and the sole-support comprise an adjusting-screw f^4 , having a head f^5 , which screw meshes in a threaded hole in the cap-plate f^3 , the outer edge of which head enters a recess f^6 , extending across the face of the 120 slide f' near its lower end. The slide extends below the bracket and cap in order to permit the engagement of the screw-head therewith and also for the purpose of locating the head of the screw in an accessible position. A set or lock screw f^9 is carried by the bracket F' and is adapted to be screwed against the slide to fasten it and the sole support or rest in a stationary position after they have been adjusted. The bracket F' is 130 adjustably attached to the section a' of the main frame, being shown so attached by a screw-stud f^7 , which passes through a slot f^8 in the bracket, and by means of this slot and

the screw the bracket is enabled to be adjusted horizontally, which provides horizontal adjustments for the sole rest or support. The inner end of the bracket is squared to fit a squared horizontal recess in the side of the frame, (indicated by dotted lines in Fig. 3,) although it may be otherwise supported thereon. To assist the operator in guiding the shoe under the knife, I have shown a gage 10 adjacent to the shoe-support. The gage H is located back of the sole support or rest and somewhat above it, and it serves as a means for determining the line of action or cut of the reciprocating knife or cutter c' in the shoe or article which may be held against it. It may be a stationary gage, or it may be provided with rotation, in which event it becomes a feeding or antifriction gage, and when it is so employed I prefer to rotate it by means of 15 a spirally-threaded wheel h' on a shaft h and a spirally-threaded wheel h², the axis of which is at a right angle to the axis of the first-named wheel and which is carried at the end of a hollow horizontal shaft h³. (See Figs. 1 and 4.) The said shaft h³ is supported at one end by a stud attached to a bracket h⁴ and at the other end by the bracket h¹⁰, and said shaft has a beveled gear h⁵, with which a beveled gear h⁶ at the lower end of a shaft 20 h⁷ engages. This shaft h⁷ is in turn connected with the main shaft B by means of a worm-wheel h⁸ at the upper end of shaft h⁷, meshing with a worm h⁹ upon the main shaft. (See Fig. 2.) Shaft h⁷ is journaled in suitable bearings carried by the main frame. 25 The gearing is of a size to provide the gage with relatively slow rotation. The gage is provided with means whereby it may be vertically and horizontally adjustable in relation to the sole support or rest F. It is vertically adjusted by means of a sleeve m, through which the shaft h extends, which sleeve has an exterior screw-thread m', screwing into a threaded hole m² at the forward end of a slide 30 m³. The sleeve m has an enlarged section or head M, by which it may be turned. It will thus be seen that the support F and gage H are supported and adjustable independently of each other, and it is evident that a skillful operator could guide a shoe on the support F under the knife without utilizing the gage H as a guide. 35

It will be understood that the sleeve m furnishes a bearing for the gage-shaft h and that it also provides means whereby the gage-shaft and gage may be vertically adjusted. That this adjustment may be made without disengaging the threaded wheels h' h² the threaded wheel h' is made longer than would otherwise be necessary. A stud m⁴ extends through an opening in the slide m³ and bears constantly against the outer surface of the sleeve m. It is pushed inward by a lever or arm m⁵, pivoted at m⁶ and against which a spring m⁷ bears, so that the stud m⁴ is forced and held by the yielding pressure of the spring against the sleeve. The slide m³ has a round sec-

tion m⁸, which slides and is held in opposed holes m⁹ in the frame A, and means are provided for adjusting the slide horizontally toward and from the sole-rest F. For this purpose I have shown an adjusting-screw m¹⁰, fastened to the frame A and extending outward therefrom, and an adjusting-nut m¹¹, mounted upon said screw m¹⁰ and which engages the slide m³ by means of a forked connecting-arm m¹² extending therefrom. 70

To permit the horizontal movement of the gage without disengaging the threaded connecting-wheels h' h², the wheel h² upon the horizontal shaft is made longer than would otherwise be required. The bevel-gear h⁵, the threaded wheel h², and their operating-shaft may be covered by a curved cover-plate n. 75

It will be understood that when the gage H is not adapted to have rotary movement the operating-wheels h' h² and shafts h³ h⁷ and their connecting-gearing may be dispensed with. 80

The operation is as follows: The knife-bar case having been moved to one side of the shoe-support, the shoe is placed over the end of said case and is then moved with the knife-bar case over the work support or rest, whereupon the knife-bar case is automatically locked and maintained locked with the knife-bar and knife in operative position within the shoe. The shoe-sole thus resting upon the sole-support its edge is brought in contact with the gage, and this causes the inner surface of the sole and the edge of the upper to be separated from the under surface of the knife-bar case. The machine is then set in operation and the shoe is fed and guided by the operator in a manner to cause it to be presented in any desired order of movement to the action of the cutter, which is rapidly reciprocating within the cavity of the shoe, and by adjusting the gage to any desired position and holding the edge of the sole in contact therewith the line of the cut made by the knife may be predetermined. When a rotating gage is employed, the edge of the sole is advanced by the gage, as well as located by it, so that the following sections or parts of the sole edge are to a degree automatically gaged. 90 100 105 110 115

It is desirable that the knife be centrally located in respect to the sole-support and the gage. Nice fitting of parts would be necessary to so locate the knife were it not that means are provided whereby it may be more readily accomplished. This result is obtained by making the locking-pin d upon the arm d³ of the rock-shaft adjustable lengthwise upon the arm, and a change in its position on the arm will of course vary the position of the lower end of the knife-bar case of the knife. Any means for adjusting the pin horizontally may be employed, and I have represented as one means a longitudinal slot in the said arm d³, in which said pin is horizontally movable, the pin being locked to the arm in any desired place by a washer and nut. 120 125 130

I may say that the apparatus herein de-

scribed may be used for trimming out any surface material from the interior of a shoe or other hollow article and that the details of construction shown and described may be varied without departing from the spirit of my invention.

Having thus fully described my invention, I claim and desire to secure by Letters Patent of the United States—

- 10 1. In a boot or shoe machine for trimming out uppers, the combination of a reciprocative knife or cutter supported from above to operate within the boot or shoe, and means for reciprocating the knife or cutter within the latter, with a rigid shoe-support located beneath said cutter, and means to permit the knife or cutter to be held in an operative or in an inoperative position, substantially as described.
- 15 2. In a boot or shoe machine the combination of a depending knife or cutter adjustably supported from above to swing on a horizontal axis, means for actuating said knife or cutter, and means to permit the knife or cutter to be held in an operative or in an inoperative position, and a support for a shoe located beneath the knife or cutter, substantially as described.
- 20 3. The combination of a knife or cutter support, a guide therefor supported from above to have adjustment on a horizontal axis, means for actuating the knife or cutter support, means to permit the knife or cutter to be held in an operative or in an inoperative position, and a support for the work located beneath the knife or cutter support, substantially as described.
- 25 4. The combination of a knife-support, a guide therefor adjustably supported from above to have adjustment on a horizontal axis, means for actuating the knife-support, and an adjustable support for the work located beneath the knife, substantially as described.
- 30 5. The combination of a knife-support adapted to enter a shoe, means for actuating the same, a work-support below the knife-support, and a guide for the work adjustable independently of the work-support, substantially as described.
- 35 6. The combination of a knife-support adapted to enter a shoe, means for supporting and actuating the same, an adjustable work-support below the knife-support, and a guide for the work adjustable independently of the work-support, substantially as described.
- 40 7. The combination of a reciprocative knife or cutter, means for supporting and reciprocating the same within a shoe, a work-support below the knife or cutter, and a guide for the work, said guide being adjustable independently of the support, substantially as described.
- 45 8. The combination of a reciprocative cutter, means for supporting and operating the same within a shoe, an adjustable support

for the work below the cutter, and an adjustable guide for the work, said guide being adjustable independently of the support, substantially as described.

70

9. The combination of a knife-bar case or guide adjustably supported from above, a knife-bar carried therein, means for actuating said knife-bar, a support for the work located beneath the knife-bar, and a guide for the work adjustable independently of said support, substantially as described.

10. In a machine of the character specified, the combination with a shoe-support, of a movable knife-bar case or arm adjustably supported above said shoe-support and adapted to enter a shoe, means to permit said knife-bar case or arm to be held in an operative or in an inoperative position, a knife-bar carried inside said case or arm, and means for giving a rapid reciprocating movement to said knife-bar, substantially as described.

11. In a machine for trimming out uppers, the combination with a hollow knife-bar case pivotally suspended from above, of means for locking it rigidly in an operative or in an inoperative position whereby it acts as a guide for a rapidly-moving knife-bearing bar therein incased inside a shoe to trim out surplus material.

12. The combination of a knife-support, an adjustable guide therefor, means for holding said guide in an operative or in an inoperative position, and a work-support located in line with said knife-support in the normal position of the latter, substantially as described.

13. In a machine of the character specified, the combination with a shoe-support, of a knife-bar case or arm carried above said support, a knife-support guided by said case or arm, means for holding said knife-bar case and knife in an inoperative position at one side of said shoe-support, means for locking it in an operative position above said support, and means for giving a rapid reciprocating movement to said knife, substantially as described.

14. The combination in a machine of the character specified, of a movably-suspended knife-bar case, a reciprocative knife carried at its lower end, a support or rest for an outsole, and means for adjusting said support or rest horizontally, substantially as described.

15. In a machine of the character specified, the combination of a movably-suspended knife-bar case, a reciprocative knife carried at its lower end, a support or rest for an outsole, and means for adjusting said support vertically and horizontally.

16. The combination in a machine of the character specified of a movable knife-bar case, a reciprocative knife carried at its end, a support or rest for the outsole, and a gage against which the edge of the sole may be held.

95

105

110

115

120

125

130

17. The combination in a machine of the character specified of a suspended knife-bar case, a reciprocative knife carried at its lower end, a support or rest for an outsole, an edge-gage independent of said support, and means for adjusting said gage vertically, substantially as described.
18. The combination in a machine of the character specified of a knife-bar case suspended above the work, a reciprocative knife carried at its lower end, a support or rest for an outsole, a gage adjacent to the support and means for adjusting said gage laterally relative to said support, substantially as described.
19. The combination in a machine of the character specified of a knife-bar case, a reciprocative knife carried at its lower end, a support or rest for an outsole, a gage independent of said work-support and means for adjusting said gage vertically and laterally relative to said outsole-support and the work, substantially as described.
20. The combination in a machine of the character specified of a knife-bar case, a reciprocative knife carried at its lower end, a support or rest for an outsole, means for adjusting said support or rest vertically, a gage, and means for adjusting it vertically relative to the outsole-support of the work, substantially as described.
21. The combination in a machine of the character specified of a knife-bar case, a reciprocative knife carried at its end, a support or rest for an outsole, means for adjusting it horizontally, a gage, and independent means for adjusting it horizontally relative to said outsole-support, substantially as described.
22. In a shoe-machine the combination of a shaft, a depending cutter-support connected therewith to be operated thereby and adapted to enter a shoe, a guide for the cutter-support movably supported and having its point of support concentric with said shaft, and a work-support beneath said cutter-support, substantially as described.
23. In a shoe-machine, the combination of a shaft, a depending cutter-support, a crank connecting the shaft and said support, a depending guide for said cutter having its point of support concentric with the shaft and adapted to enter a shoe, and a work-support beneath said guide, substantially as described.
24. In a shoe-machine, the combination of a shaft, a depending cutter-support, means for operating the latter by said shaft, a pivotally-supported guide for the cutter-support, a work-support beneath said guide, and a guide for the work independent of the work-support, substantially as described.
25. In a shoe-machine, the combination of a shaft, a depending cutter-support, means connecting the latter with the shaft for operating said support, a depending guide for the cutter-support adapted to enter a shoe and having a sleeve journaled on said shaft, and a work-support beneath said guide, substantially as described.
26. The combination of a cutter, the guide for the same, the sole rest or support, its supporting-slide, the bracket in which the said slide is mounted attached to the frame to be horizontally adjustable in relation thereto, and an adjusting-screw located substantially as described and adapted to engage the slide as specified.
27. The combination of a slide and means for adjusting it horizontally, a threaded sleeve meshing in a threaded hole in said slide, means to permit the sleeve to be rotated, and a shaft extending through a hole in said sleeve and carrying a gage at its upper end, as and for the purposes described.
28. The combination of a slide, means for adjusting it horizontally, a threaded sleeve meshing in a threaded hole in said slide, means to permit the sleeve to be rotated, a shaft extending through a hole in said sleeve, carrying at its upper end a gage and at its lower end a long threaded wheel, and a long threaded wheel mounted on a horizontal shaft to engage said first-named wheel and connected with the main shaft of the machine, substantially as described.
29. The combination of a knife-bar case pivoted at its upper end, whereby its lower end is adapted to be swung laterally from the sole rest or support, with the latch to lock and maintain it in operative position, substantially as and for the purposes set forth.
30. The combination of a knife-bar case suspended as described, a latch or lock for locking it with the knife-bar and knife in operative position and holding them so located, a treadle connected with the latch or lock to disengage it from the said knife-bar case to permit the latter to be moved laterally, the said latch and knife-bar case being adapted to automatically engage upon the movement of said knife-bar case to an operative position.
31. The combination of a cutter or knife, its operating-shaft, and means for automatically rotating the latter, comprising a heart-shaped cam secured to said shaft, a pin adapted to be brought into contact with said cam, and means for operating said pin, substantially as described.
32. The combination of a knife-bar case, a reciprocative knife carried thereby, its actuating-shaft, a knife-bar-case-unlatching device, a device upon the shaft for rotating it, a treadle, and means for connecting it with the unlatching device and with the shaft-rotating device, whereby they may be simultaneously operated by a single motion of the treadle.
33. The combination of a support for a shoe or its sole, with a knife adapted to be inserted within the fore part of the shoe and located adjacent to said support so that the part of the shoe to be cut can be placed between said support and said knife, means

for operating said knife, and a feeding-gage adapted to gagingly feed the shoe or its support as the knife operates.

34. In a machine of the character specified, 5 the combination with a work-support of a sole-edge gage, a knife-guide suspended above said work-support, a rapidly-reciprocatative knife in said guide, means for operating said knife, and means for adjusting said knife- 10 guide and knife laterally with relation to said work support and gage, substantially as described.

35. The combination of a knife-bar case having a latching-recess c^7 , the latch d , and 15 means for varying its horizontal position on its operating-arm.

36. The combination in a machine of the character specified of a suspended laterally-movable knife-bar case, a knife carried at its 20 lower end, means for reciprocating said knife, a support or rest below the knife for the bottom of the outsole, and means for adjusting said support or rest vertically.

37. The combination of a movably-suspended 25 knife-bar case C having an inwardly-extending end c^4 , a reciprocative knife-bar within said case, the lower end of which is bent inwardly, and a knife attached to the lower end of said bar, substantially as de- 30 scribed.

38. The combination of a knife-bar case C having an enlargement at its upper end, a shaft, a counterbalance, a crank and pitman link located in such enlargement, said knife- 35 bar case having an inwardly-turned end, a knife-bar having its lower end inwardly turned and contained in the inwardly-turned end of said case, said knife-bar being con-

nected with said pitman, and a knife connected to the lower end of the knife-bar, substantially as described. 40

39. The combination of knife-bar case C having an enlargement at its upper end adapted to be suspended upon a shaft and also having a bent or inwardly-extending lower end 45 or foot closed upon its sides and top and open at its bottom, and a reciprocative knife-bar in said case having a bent or inwardly-extending lower end, and a knife or cutter attached thereto, substantially as described. 50

40. In a machine for trimming out uppers from the inside of a shoe, the combination with a depending inwardly-extending knife-bar case adapted to be inserted within a shoe, of a rapidly-reciprocative knife in said case, 55 means for operating said knife, means for moving said knife and case laterally with respect to a work-support, a work-support, and means for locking said knife in operative relation to said work-support, substantially as 60 described.

41. In a boot and shoe machine for trimming out uppers, the combination of a movable knife-bar case having an inward and downward extension, a reciprocative knife-bar within the case having an inward and downward extension, a knife attached to the inner end of the knife-bar, and a sole-rest formed by the top of an upwardly and inwardly extending arm, substantially as de- 70 scribed. 65
